A. WEISS.
CIGAR VENDING HUMIDOR.
APPLICATION FILED APR. 4, 1916.

1,235,862.

Patented Aug. 7, 1917.

Fig. 1.

UNITED STATES PATENT OFFICE.

ALEXANDER WEISS, OF PHILADELPHIA, PENNSYLVANIA.

CIGAR-VENDING HUMIDOR.

1,235,862.

Specification of Letters Patent.

Patented Aug. 7, 1917.

Application filed April 4, 1916. Serial No. 88,911.

To all whom it may concern:

Be it known that I, ALEXANDER WEISS, a subject of the Czar of Russia, residing at Philadelphia, in the county of Philadelphia and State of Pennsylvania, have invented 5 new and useful Improvements in Cigar-Vending Humidors, as set forth in the annexed specification.

My invention relates to new and useful 10 improvements in cigar vending humidors, and has for its object to provide an exceedingly simple and effective device of this character, whereby an entire box of cigars including the box may be placed in the 15 humidor and the whole tightly sealed or closed, so that the moisture within the humidor will be prevented from escaping, and thus keeping the cigars contained in the 20 box in good condition until the entire box of cigars has been sold.

A further object of the invention is to provide a cigar vending humidor having a body consisting of suitable inclosed walls, an upwardly projecting chamber at the rear of 25 the body and two lids or closing leaves hinged thereto, one of the closure leaves adapted to close the rear of the body and upwardly projecting chamber, but leaving the upper end of said chamber opened, 30 through which projects the lid of the cigar box when a box containing cigars is placed in the humidor.

Another object of the invention is to provide in combination a humidor adapted to 35 hold a cigar box with cigars therein, said humidor having a lid which may be readily opened by the storekeeper, so that the cigars may be sold directly from the humidor, a cigar perforator on one end thereof and a 40 match safe or holder.

A still further object of the invention is to provide a cigar vending humidor in which the ordinary cigar box in which cigars are sold with the cigars therein may be 45 placed in the body of the humidor with the lid of the ordinary cigar box projecting outside of the body of the humidor, so that the trade mark or other advertising matter on the lid of the cigar box may be readily seen.

With these ends in view, this invention 50 consists in the details of construction and combination of elements hereinafter set forth and then specifically designated by the claims.

In order that those skilled in the art to 55 which this invention appertains, may under-

stand how to make and use the same, I will describe its construction in detail, referring by numerals to the accompanying drawing forming a part of this specification, in 60 which—

Figure 1 is a front elevation of my improved cigar vending humidor showing a box of cigars therein.

Fig. 2 is an end view thereof. 65

Fig. 3 is a section on the line 3—3 of Fig. 1; and

Fig. 4 is an enlarged fragmentary sectional view of one end of the humidor, the cigar perforator and match holder. 70

In carrying out my invention as here embodied 2 represents the body of the humidor consisting of a bottom wall 3, a front wall 4 and end walls 5 and 6. The end walls 5 and 6 have projections 7 rising therefrom at 75 the rear ends, to which is secured a front wall 8 arcuate in shape or cutaway as plainly shown in Fig. 1 for a purpose to be hereinafter described. The front wall 4 and one of the end walls as 5 are provided 80 with transparent panels 9, such as glass. To the body at the rear end thereof is hinged a lid 10 as at 11, and this lid is provided with a handle 12 projecting rearwardly to a point in back of and above the body of the humidor, whereby the lid 10 may be readily and quickly raised, and this lid is provided with a transparent panel 13 such as glass.

To the bottom wall 3 of the body at the rear edge thereof is hinged a leaf 14 as at 15, 90 said leaf having a portion thereof projecting at an angle to the main part to form an extension 16, said extension being situated between the two extensions 7 of the side walls of the body and lying parallel with the wall 95 8, so that when the leaf 14 is closed, a chamber 17 is formed which projects upwardly from the body at the rear thereof, and said chamber is in communication with the interior of the body. In order that the leaf 14 may be held in its closed position I provide the same with a suitable fastening device such as a hook 18 engaging a pin 19.

When the humidor is in use a cigar box 20 with the cigars therein is placed in the 100 body of the humidor, and the lid or cover 21 of the cigar box is placed within the chamber 17 in a raised position, so that said lid projects out of said chamber, and considerably above the same, said chamber being 105 open at the top.

In order that the humidor may be tightly

closed or sealed, I provide the front wall 8 of the chamber 17 with a rib 22 against which rests the front face of the cigar box cover 21, and a similar rib 23 is formed 5 upon the hinged leaf 14 and is adapted to engage the rear face of the cigar box cover 21. The humidor is supported by suitable legs 24, the rear ones being of greater length than the forward ones, so that the humidor 10 is held in a tilted position, thereby permitting persons to readily see the goods displayed.

The end wall 6 is solid and is preferably formed of metal, as are the other walls of 15 the humidor, and on the inner face of this wall 6 is secured a pair of parallel tracks 25 in which are adapted to slide the flanges 26 of the moistener casing, said casing adapted to contain a suitable absorbent material for 20 holding a liquid, such as water, whereby the air in the humidor will be moistened and the cigars maintained in a proper moistened condition.

The end wall 6 is also provided with a 25 number of outwardly projecting bosses 28 through which screws 29 are threaded into one of the walls of the cigar perforator 30, the same consisting of side walls 31 and a bottom wall 32 and a top wall 33 having an 30 opening 34 therein. To the top wall 33 are secured a number of rods 35 depending therefrom and having enlargements 36 on the lower ends. On these rods is adapted to slide the inverted conical shaped holder 37 having 35 a hole 38 in its apex into which is adapted to project the point perforator 39 when the holder 37 is forced downward against the action of the springs 40 coiled about the rods 35 and engaging the enlargements 36 40 and the flange of the holder 37. The perforator 39 projects upwardly from the bottom wall 32 and is securely fixed in position, so as to remain stationary.

When it is desired to perforate a cigar the 45 end thereof is inserted in the holder 37 which prevents the wrapper of the cigar from cracking or splitting, and by bringing a certain amount of pressure to bear upon the cigar the holder 37 will be forced downward against the action of the springs 40, so as to cause said holder and the cigar to pass over the perforating pin 39 and pierce the end of the cigar. As soon as the pressure upon the holder 37 is released by the 50 removal of the cigar, the springs 40 will again return said holder to its normal position at the upper end of the perforator casing.

To some suitable part of the perforator 60 casing may be secured the match holder or safe 41, so that a purchaser of a cigar may remove a match and strike the same upon the serrations 42.

In practice the cigar vending humidor is 65 placed upon the counter or show case of a

store and the box of cigars placed therein with the cover 21 of the cigar box projecting out of the open end of the chamber 17. Because of the arcuate shape of the upper edge of the front wall 8 of the chamber 17, none 70 of the advertising matter upon the cigar box is hidden, and a person entering the store can readily read the same, and a probable purchaser will be able to identify the goods in the humidor by said advertising 75 matter upon the cigar box cover.

When a purchaser wishes to purchase a cigar it is only necessary for the storekeeper to press the handle 12 downward which will 80 raise the lid 10 and open the humidor, so that the purchaser may pick out the cigar desired from the contents of the cigar box.

When the cigar box is empty the same may be readily removed by opening the closure leaf 14 and swinging the same downward, thus simultaneously opening both the body and chamber 17, so as to permit the withdrawal of the cigar box, and after said cigar box is removed it may be readily replaced by another one.

Of course I do not wish to be limited to the exact details of construction here shown, as these may be varied within the limits of the appended claims without departing from the spirit of my invention.

Having thus fully described my invention, what I claim as new and useful, is—

1. A cigar vending humidor consisting of a body comprising a bottom, a transparent front wall, a transparent end wall and a solid end wall, extensions projecting upwardly from the side walls of the body, a front wall having an arcuate upper edge secured to said extensions thereby forming a chamber open at its upper end, a transparent lid hinged to the upper portion of the body at the rear thereof, a handle projecting therefrom, a leaf hinged to the bottom of the body at the rear thereof, an extension formed with said leaf lying parallel with the front wall of the chamber when the leaf is closed, and means for fastening said leaf in a closed position.

2. A cigar vending humidor consisting of a body comprising a bottom, a transparent front wall, a transparent end wall and a solid end wall, extensions projecting upwardly from the side walls of the body, a front wall having an arcuate upper edge secured to said extensions thereby forming a chamber open at its upper end, a transparent lid hinged to the upper portion of the body at the rear thereof, a handle projecting therefrom, a leaf hinged to the bottom of the body at the rear thereof, an extension formed with said leaf lying parallel with the front wall of the chamber when the leaf is closed, means for fastening said leaf in a closed position, and diametrically opposite ribs formed upon the front wall of the 130

chamber and the leaf for the purpose described.

3. In a device of the character stated a box, a body open at the top and rear thereof, a chamber projecting upwardly from the rear portion of said body in communication therewith, said chamber being open at the rear and top thereof, a lid hinged to the

body at the rear thereof for closing the top of the same, and a leaf hinged to the bottom 10 of the body at the rear thereof for closing the rear of the body and chamber.

In testimony whereof, I have hereunto affixed my signature.

ALEXANDER WEISS.
